Patented Nov. 19, 1918.

UNITED STATES PATENT OFFICE.

FRANK KING, OF FOUNTAIN, COLORADO.

ANTISKIDDING DEVICE.

1,285,224.

Specification of Letters Patent.

Patented Nov. 19, 1918.

Application filed August 30, 1916. Serial No. 117,723.

To all whom it may concern:

Be it known that I, FRANK KING, a citizen of the United States, residing at Fountain, in the county of El Paso and State of Colorado, have invented certain new and useful Improvements in Antiskidding Devices, of which the following is a specification.

This invention relates to anti-skidding devices and is especially adapted for use in connection with automobile wheels.

More specifically, it is the object of this invention to provide a plurality of spurs or ground engaging elements in connection with each wheel, the same being normally positioned in an inoperative position and being so connected that the movement thereof will be controlled by a lever adjacent the operator's seat.

20 A still further object of this invention resides in the production of a device of the kind above described that is simple in construction, efficient in operation and consists of the minimum number of parts.

25 With these and other objects in view, this invention consists of certain novel constructions, combinations and arrangement of parts, as will be hereinafter fully described and claimed.

30 In the accompanying drawings:

Figure 1 is a plan view of a pair of wheels, the axle casing and the improved device mounted thereon.

35 Fig. 2 is a fragmentary view in elevation of a portion of a wheel equipped with this improved device.

Fig. 3 is a vertical sectional view taken through the disk housing used with this invention having a disk mounted therein.

40 Fig. 4 is a section taken on line 4—4 of Fig. 2.

Referring to the parts by reference numerals, the axle casing is designated by the numeral 10 and the wheels in their entirety by the numeral 11. On the felly of the wheel is provided a supporting ring 12 the same having at uniformly spaced intervals thereon the projections 13 through which the means 14 is passed to rigidly engage the

50 same with the felly of the wheel. It is to be observed that the anti-skidding device is to be attached between spokes of the wheel. On this ring 12 are a plurality of uniformly spaced brackets, one of which is shown in 55 the accompanying drawings and designated by the numeral 15, each of the said brackets

having passed therethrough a rod 16 that terminates in one end with a tapped head 17 into which is threaded the ground engaging element 18. It is to be noted that this 60 ground engaging element 18 is preferably threaded into the tapped head 17 so that when worn it can be replaced.

A second bracket is adapted to be secured in alinement with each of the brackets 15, 65 preferably on the hub of the wheel the said brackets being designated by the numeral 19. On the rod 16 is a coil spring 20 the same being in abutment with the plate 21 that is secured on the rod by means of the 70 pin 22 and at the opposite end thereof from that of its engagement with the plate 21, the same is in engagement with the sliding sleeve 23 which has its movement on the rod 16 limited by the adjustable collar 24. Having 75 described that portion of my invention that is attached to the wheel it is to be noted that although I have only described one of the members that a plurality of the same are provided with each wheel preferably 80 spaced between the spokes of the wheel. I will now proceed to describe the operating means of the device above set forth.

Adjacent each of the wheels is provided a disk casing 25 that has secured therein a 85 disk 26 which has at uniformly spaced intervals thereon, pairs of ears 27 which pivotally connect the strips 28 with the disk 26. It is to be observed that these strips 28 are pivotally connected with the sliding sleeve 90 23 as at 29. It is to be observed that the casing 25 is provided with an overhanging flange 30 to retain the strips 26 in the same. Each of the housings 25 is provided with a reduced collar 31, the same being of such 95 size as to receive the axle casing and having connected therewith the connecting strips 32 that have their opposite ends in connection with the sliding sleeves 33. A toggle composed of the arms 34 is connected with the 100 sleeves 33 and an operating rod 35 is pivotally secured to the arms 34 at their pivotal connection with each other. A suitable bearing 36 is secured on the axle casing for the rod 35.

It is to be understood that when the rod 35 is moved forwardly the disk casings 25 are moved outwardly relatively to the rod 35 and the rods 16 are moved outwardly from the hub of the wheel to which they 110 are attached and the ground engaging elements 18 beyond the tread of the tire.

It is obvious that minor changes may be made in the form and construction of this invention without departing from the material parts thereof. It is therefore not wished to confine the invention to the exact form herein shown and described, but it is wished to include all such as properly come within the scope claimed.

I claim:

10. The combination with a wheel having a ring secured to the felly thereof, of an anti-skidding means for said wheel comprising a bracket on said ring, a rod slidable through said bracket, a ground engaging element on the end thereof, a spring on said rod having one end thereof secured from movement, a

sleeve on said rod and in engagement with the opposite end of said spring, means for limiting the movement of said sleeve and operating means for said sleeve to move said ground engaging element into engagement with the ground by engagement with the spring and move the said element out of engagement with the ground by engagement with the means for limiting the movement of the said sleeve.

In testimony whereof I affix my signature in presence of two witnesses.

FRANK KING.

Witnesses:

LORREN T. GORE,
C. W. CRAWFORD.
